UNITED STATES PATENT OFFICE

HERBERT E. EDWARDS, OF BROOKLINE, MASSACHUSETTS

SHOE BOTTOM ORNAMENTING MACHINE

Application filed November 28, 1931. Serial No. 577,776.

The present invention relates to machines for use in the manufacture of shoes, and more particularly to a machine for ornamenting shoe bottoms.

- 5 Because of the recognized sales appeal of shoes so marked, it has been proposed heretofore to mark the same series of parallel lines twice in succession across the bottom of a shoe in a manner to cause the first lines 10 to be crossed by the second lines and thus define a plurality of lozenges, diamonds or geometrical figures other than rhombs on the shoe bottom. In order to perform this 15 shoe bottom cancelling operation heretofore, an operative would lay upon the shoe bottom a thin plate having about sixteen parallel slots and then with some form of a scribing tool mark a line on the shoe bottom employing each slot in succession as a guide. 20 Then when the first sixteen lines had been marked the slotted plate would be shifted to a new location on the marked shoe bottom and the marking operation would be repeated to cross the first sixteen lines with the 25 second sixteen lines. As the other shoe in the pair and the other shoes in the case lots would have to be similarly marked the cancellation operation proved to be exceedingly slow, laborious and expensive. 30 The principal object of the present invention is to produce a machine for performing the cancelling operation in a rapid, reliable and economic manner.

To the accomplishment of this object, and 35 such others as may appear hereinafter, the features of the invention relate to certain devices, combinations and arrangements of parts hereinafter described and then set forth broadly and in detail in the appended 40 claims which possess advantages which will be apparent to those skilled in the art.

The various features of the present invention will be understood readily from an inspection of the accompanying drawings illustrating the best forms of the invention at 45 present devised, in which,

Figure 1 is a view in elevation of the shoe bottom ornamenting machine;

Fig. 2 is a view in plan;

50 Fig. 3 is a view in sectional elevation on

the line 3—3, Fig. 1, the cancelling tools, however, being shown engaged with the shoe bottom;

Fig. 4 is a detail view in sectional elevation of the toe saddle;

Fig. 5 (Sheet 1) is a view in sectional plan on the line 5—5, Fig. 3;

Fig. 6 (Sheet 2) is a detail view in elevation of the cancelling tools for scratching the criss-cross lines on the shoe bottom;

Fig. 7 is a detail view in sectional elevation on the line 7—7, Fig. 6;

Fig. 8 is a plan of the shoe showing its bottom ornamented with cancellate lines;

Fig. 9 is a detail view of a detachable head 55 carrying a plurality of knurling tools differently mounted from the knurling tools illustrated in Figs. 1 and 3;

Fig. 10 is a detail view in sectional elevation on the line 10—10, Fig. 9, and

Fig. 11 is a detail view in sectional plan on the line 11—11, Fig. 10.

In the embodiment of the invention illustrated in Figs. 1, 2 and 3 the cancelling tools comprise a series of knurling wheels 12, 75 herein shown as twenty-two in number, each of which is rotatably mounted in a yoke 13 secured to the free end of a leaf spring 14. The upper end of the spring 14 fits into an opening 15 formed in a rectangular head 16 80 and is secured thereto by a screw 17.

The head 16 is tapped at 18 to receive the shanks of two screws 19, the construction being such that the head 16 is detachably connected to a carrier 20 mounted to travel 85 on a pair of spaced rails 21. The carrier 20 comprises a flat plate 22 mounted to slide upon the upper faces of the rails 21. Between the rails and beneath the plate 22 is a rectangular block 23. Mounted to slide upon the bottom faces of the rails 21 is a flat plate 24 to which is secured a cross-bar 25 containing the screws 19 for the head 16. The plates 22 and 24 and the block 23 are secured together 90 by four screws 26 (Fig. 1). The carrier 20 may be reciprocated along the rails 21 by means of a handle 27 grasped by the operative.

The rails 21 are joined at their ends by webs 28 which act as stops for limiting the movement of the carrier 20 in either direc- 100

tion. The webs 28 are carried by the upper ends of posts 29 the lower ends of which are provided with flanges 30 to facilitate their attachment to a flat base 31 which is mounted 5 on a work bench in a shoe factory. The rails 21 and the webs 28 comprise a frame for supporting the carrier 20.

In order to support a shoe beneath the rails 21 and between the posts 29, the base 31 is 10 provided with a work support of the toe saddle and heel spindle type. To this end the base 31 is engaged by a thin flat plate 32 secured to the bottom of a yoke 33, comprising the work support frame and bolted to the 15 base 31 in a manner permitting the work supporting frame to be rotated about a fixed axis on the base 31. Rising from the body portion of the yoke 33 is a post 34 (Figs. 3 and 4) the upper end of which is cut on 20 curved lines to form the central stationary section 35 of a toe saddle. Hinged to the opposite sides of the post 34 are blocks 36 which are provided with curved internal side faces adapted to fit the curved lateral sides of 25 the central section 35. The blocks 36 are provided also with inclined faces 37 which cooperate with the central section 35 to form a saddle for supporting the toe of an inverted shoe 38 from which the last 39 has not yet 30 been pulled. The faces 37 are lined with felt 40 to prevent the vamp portion of the shoe from being marred.

In order to adapt the toe saddle to support shoes having different widths or styles of 35 toes, the blocks 36 may be expanded away from the post 34. To this end a coiled spring 41 is interposed between the post 34 and each block 36. To draw the blocks 36 towards 40 each other against the tensions exerted by the springs 41 the upper end of the post 34 carries the central portion of a threaded rod 42 the ends of which extend loosely through openings 43 formed in the post 34 and the blocks 36. The free ends of the rod 42 are 45 provided with wing nuts 44 between which and the adjacent block 36 a washer 45 is interposed. With this construction, the toe saddle is either contracted or expanded depending 50 upon the direction in which the nuts 44 are turned.

The heel spindle comprises a post 46 the upper end of which fits into the usual socket formed in the heelpart of the last 39. The lower end of the post 46 is threaded into a 55 block 47 provided with trunnions 48 which turn in a slide 49 the lateral sides of which are grooved to embrace the edges of plates 50 secured to the arms of the yoke 33. The block 47 is engaged by a leaf spring 51 (Fig. 60 3) secured to the bottom of the slide 49. With this construction the heel spindle 46 can turn on its trunnions and thus adapt itself automatically to variations in the angularity of the heel spindle sockets in the lasts. 65 The spring 51 also exerts pressure on the

heel spindle in a direction tending to hold the toe of jacked shoe in contact with the toe saddle.

In order to adapt the machine to support shoes varying widely in size, necessitating the use of heel spindles 46 varying in length, the base 31 is provided with a plurality of screw threaded openings 52 which receive the screw threaded ends of heel spindles 53 of different lengths. These spindles 53 may be interchanged with the heel spindle 46. To increase their usefulness and to reduce the number of auxiliary heel spindles 53, their upper ends are provided with screws 54 so that their effective lengths may be varied.

In order to maintain the shoe bottom in the same plane, or approximately so, notwithstanding variations in the lengths and heights of the shoes mounted upon the work support, the plates 50 incline upwardly towards the toe saddle. This construction provides means for adjusting the toe saddle and heel spindle relatively both longitudinally and vertically. The longitudinal adjustment takes care of the variations in the lengths of the shoes. The vertical adjustment locates the bottoms of the forepart of the shoes substantially in the same plane notwithstanding their variations in heights due to variations in lengths.

In order to lock the slide 49 in the position to which it has been adjusted one of its grooved edges on the upper side thereof is provided with teeth 55 engaged by a spring pressed pawl 56 pivoted upon the adjacent plate 50. The movement of the slide 49 is limited in one direction, by a vertical pin 57 carried by one of the plates 50, and in the other direction, by a lateral pin 58 carried by one of the arms of the yoke 33.

After the shoe has been jacked it may be positioned with it median line normal to the longitudinal axis of the path of the carrier 20 so that the operative may, by grasping the handle 27, reciprocate the carrier 20 to cause the knurling wheels to roll across the shoe bottom and knurl a series of parallel lines thereon. As each wheel 12 is mounted upon the end of a leaf spring 14 and as the plane of the forepart of the shoe is slightly above the normal plane of the bottom of the wheels 12 they automatically and independently adapt themselves to the curvature of the shoe bottom as they roll thereover. After the carrier 20 has been reciprocated to transfer the wheels 12 from the position of Fig. 1 to a position at the opposite side of the shoe, the work support may be rotated on its pivot to bring the median line of the shoe into a position normal to its first position and then the wheels 12 may be returned to the position of Fig. 1, thereby knurling a series of parallel lines on the shoe bottom normal to the first series of parallel lines. The shoe bottom is

thus cancellated, that is, provided with a series of criss-cross lines.

In order that the cancellated lines may intersect in a decussate manner, instead of in a normal manner as just described, the base 31 is provided with a pair of vertical pins 59 and 60 which limit the angular movement of the work support. Each pin may be located in one of a series of openings 61 formed in the base 31. These openings are numbered in Fig. 2 from 1 to 7, but this indicia is arbitrary as it bears no relation to the size of the shoes operated upon. When the pins 59 and 60 are in the number 7 holes, for instance, the work support is swung first until stopped by engagement with the pin 60. Then the carrier 20 is reciprocated to form the series of parallel lines 62 (Fig. 8). Then the work support is swung into engagement with the stop pin 59. When the carrier 20 is returned to its normal position a series of parallel lines 63 (Fig. 8) are formed which cross the lines 62 at an acute angle. By placing the pins 59 and 60 in different holes 61 the angle at which one series of parallel lines crosses the other series may be changed, thus changing the shape of the lozenges formed between the cancellated lines.

In order to limit definitely the area of the shoe bottom cancellated and/or predetermine the outline of the cancellated area at the juncture between the ball and shank of the shoe, or wherever it is desired the cancellated area should terminate, the machine is provided with a shield 64 (Fig. 2) for a left shoe and a shield 65 for a right shoe. Each shield comprises a thin plate 66 which is lined with felt on the side engaged with the shoe. The shape of the outline of the cancellated area along its line of termination is determined by the shape imparted to the edge 67. As shown in Fig. 2 the edge 67 forms a reentrant angle but the invention contemplates shaping the controlling edge 67 in any manner found desirable or expedient. When the shield is positioned on the shoe the knurling wheels ride thereover. Some of the wheels ride over the shield on one side of the shoe, then move down into engagement with the bottom of the shoe in the space bounded by the reentrant angle formed by the controlling edge 67, and finally ride up over the shield on the opposite side of the shoe.

The thin plate 66 is mounted detachably upon a three-sided support 68 which is pivoted on the upper end of an arm 69 rising vertically from a slide 70 (Fig. 3) mounted to slide on the plate 32 in ways formed in the bottom of the yoke frame 33. The thin plate 66 of the shield 65 is detachably mounted on a support, similar to the support 68, which is pivoted to an arm 71 rising from the slide 70 on the opposite side of the shoe from the arm 69.

The slide 70 may be reciprocated to vary the location of the shields longitudinally of the shoe by means of a finger-piece 72 carried by one end of a resilient plate 73, the other end of which is secured to the slide 70. As shown in Fig. 3 the end of the finger-piece 72, engaged with the plate 73, is extended to register, one at a time, with depressions 74 formed in the upper face of a block 75 carried by the plate 32. The block 75 is provided with indicia 76 (Fig. 5) to aid the operative in adjusting the position of the shields longitudinally of the shoe.

The periphery of the knurling wheels 12 may be shaped to knurl many different kinds of marks upon the shoe bottom. In order that the marks may be printed in ink upon the shoe bottom the posts 29 are embraced by the collars 77 (Fig. 1) of supports 78 for ink pads 79. The supports 78 carry also pivoted covers 80 for the ink pads. The supports 78 may be positioned so that wheels 12 roll over the ink pads after each operating stroke. The ink picked up by the knurling wheels 12 is then transferred to the shoe bottom upon the next succeeding operating stroke. When it is desired to use the wheels 12 as knurling wheels only, the collars 77 may be loosened on the posts 29 and the supports 78 swung into the construction line position shown at the left viewing Fig. 1.

In order that the cancellated lines on the shoe bottom may comprise continuous scratches instead of printed or knurled lines, a head 81 (Fig. 6) may be connected to the cross-bar 25 in the place of the head 16. The head 81 carries a series of leaf springs 82 the free ends 83 of which are pointed to form a series of parallel grooves or scratches on the shoe bottom. These scratching tools ride over the shoe bottom and incidentally the shield, if one is used, exactly like the wheels 12. That is, the scratching tools automatically and individually adapt themselves to the shoe bottom curvatures engaged thereby.

In stead of mounting the knurling wheels 12 or the scratching tools 83 on the free ends of leaf springs they may be each mounted, as illustrated in Figs. 9, 10 and 11, upon the lower end of a slide 84 mounted to slide vertically in a head 85 capable of being connected detachably to the cross-bar 25 of the carrier 20. Near its upper end the slide 84 is provided with a lateral pin 86 which normally engages the bottom of a slot 87 formed in a cover plate 88 secured to one face of the head 85. Mounted in a separate chamber 89 in the head 85 is a coiled spring 90 which is interposed between the upper end of the slide 84 and a plate 91 forming a cover plate for the spring chambers.

With this construction the cancelling tools move vertically, instead of laterally, in adapting themselves automatically and individually to the shoe bottom curvatures.

Nothing herein explained is to be interpreted as limiting the various inventions in the scope of their application to use in connection with the particular apparatus or 5 the particular mode of operation or both selected for purposes of illustration and explanation. While the particulars of construction herein set forth are well suited to one mechanical form of the invention, it is 10 not limited to these details of construction, nor to the conjoint use of all its features, nor is it to be understood that these particulars are essential since they may be modified within the skill of the artisan without departing 15 from the true scope of the actual inventions, characterizing features of which are set forth in the following claims by the intentional use of generic terms and expressions inclusive of various modifications.

20 What is claimed as new, is:

1. In a shoe bottom ornamenting machine, the combination with a work support and a frame, of means carried by the frame and movable laterally across the work support 25 for cancelling the bottom of the shoe mounted thereon.
2. In a shoe bottom ornamenting machine, the combination with a frame, a work support and means carried by the frame and 30 movable laterally bodily across the work support for cancelling the bottom of the shoe mounted thereon, of means for confining the cross-lines to a predetermined area.

35 3. In a shoe bottom ornamenting machine, the combination with a base member, a work support mounted thereon angularly movable about a fixed axis through a predetermined arc, and a frame, of means carried by the frame and movable laterally across the work 40 support for marking the bottom of the shoe mounted upon the work support at the limit of its movement in both directions.

45 4. In a shoe bottom ornamenting machine, the combination with a work support and a frame, of means carried by the frame and movable laterally across the work support for forming a plurality of substantially parallel marks upon the bottom of the shoe mounted thereon.

50 5. In a shoe bottom ornamenting machine, the combination with a base member, a work support mounted thereon angularly movable about a fixed axis through a predetermined arc, and a frame, of means carried by the frame and movable laterally across the work support for forming a plurality of substantially parallel marks upon the bottom of the shoe mounted upon the work support at the limit of its movement in both directions.

60 6. In a shoe bottom ornamenting machine, the combination with a base member, a work support, a frame and means carried by said frame having lateral movement in opposite directions across the work support for forming a plurality of substantially parallel lines

upon the bottom of the shoe mounted upon the work support, of means connecting the work support to the base member for permitting rotation of the work support about a fixed axis relatively to said line forming means.

7. In a shoe bottom ornamenting machine, the combination with a work support angularly movable about a fixed axis in opposite directions, a frame, and means carried by 75 said frame having straight line movement laterally in opposite directions for forming a plurality of substantially parallel marks upon the bottom of the shoe mounted on the work support, of means for correlating the direction of movement of said mark forming means and the angular position of the work support to cause the parallel marks formed during the travel of said mark forming means in one direction to intersect the parallel marks formed during the travel of said mark forming means in the other direction.

8. In a shoe bottom ornamenting machine, the combination with a work support, a frame and means carried by the frame and movable laterally bodily across the work support for cancelling the bottom of the shoe mounted upon the work support, of a shield 90 for confining the cross-lines to a predetermined area.

9. In a shoe bottom ornamenting machine, the combination with a work support, a frame and means carried by the frame and movable laterally bodily across the work support for cancelling the bottom of the shoe mounted thereon, of a shield movable into and out of a position over the shoe bottom.

10. In a shoe bottom ornamenting machine, the combination with a frame, a work support having a toe saddle and a heel spindle relatively movable to accommodate different sizes of shoes, and means carried by the frame and movable laterally bodily across the work support for cancelling the bottom of the shoe mounted upon the work support, of a shield movable laterally into and out of a position over the shoe bottom and longitudinally thereof.

11. In a shoe bottom ornamenting machine, the combination with a frame, a work support having a toe saddle and a heel spindle relatively movable vertically and longitudinally to accommodate different sizes of shoes, and means carried by the frame and movable laterally bodily across the work support for cancelling the bottom of the shoe mounted upon the work support, of a shield movable laterally into and out of a position over the shoe bottom and longitudinally relatively to the toe saddle and heel spindle.

12. In a shoe bottom ornamenting machine, the combination with a frame and a work support, of means carried by the frame

and movable laterally across the work support for cancelling the bottom of the shoe mounted thereon, said means comprising a plurality of markers mounted to automatically adapt themselves to the curvature of the shoe bottom.

13. In a shoe bottom ornamenting machine, the combination with a frame and a work support, of means carried by the frame and movable laterally across the work support for cancelling the bottom of the shoe mounted thereon, said means comprising a plurality of markers each mounted to automatically adapt itself to the height and curvature of that portion of the shoe bottom engaged thereby.

14. In a shoe bottom ornamenting machine, a plurality of marking tools, a head therefor, a stem for each tool longitudinally slidably mounted in the head, and a spring mounted in the head to exert pressure on each stem.

15. In a shoe bottom ornamenting machine, a plurality of marking tools, a head therefor, a stem for each tool longitudinally slidably mounted in the head, means for limiting the movement of the stem in one direction under the influence of gravity and a spring for resisting the movement of the stem in the other direction.

16. In a shoe bottom ornamenting machine, the combination with a work support and a frame, of means carried by the frame and movable laterally across the work support for inking cancelli on the bottom of the shoe mounted thereon.

17. In a shoe bottom ornamenting machine, the combination with a work support and a frame, of means carried by the frame and movable laterally across the work support for inking a plurality of substantially parallel lines across the bottom of the shoe mounted thereon.

18. In a shoe bottom ornamenting machine, the combination with a work support and a frame, of means carried by the frame and movable laterally bodily across the work support including a plurality of marking tools for scratching substantially parallel lines across the bottom of a shoe mounted on the work support.

19. In a shoe bottom ornamenting machine, the combination with a base member, a work support, a frame, and frame carrying members supported by said base member and carrying marking material, of means carried by the frame, engageable with the marking material, and movable laterally across the work support for marking substantially parallel lines on the bottom of a shoe mounted on the work support.

In testimony whereof I have signed my name to this specification.

HERBERT E. EDWARDS.
